Albritton & Herbert[57] **CLAIM**

The ornamental design for a ball pitching machine, as shown and described.

DESCRIPTION

FIG. 1 is a perspective view of the ball pitching machine showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

FIG. - 1

FIG. -2

FIG. -3

FIG. -4

FIG. -5

FIG. - 6

FIG. - 7
